US0D1088953S

(12) **United States Design Patent** (10) **Patent No.:** **US D1,088,953 S**
(45) **Date of Patent:** **** Aug. 19, 2025**

(54) **LOCK FOR SAFETY BELTS**

(71) Applicant: **WONDERLAND SWITZERLAND AG**, Steinhausen (CH)

(72) Inventor: **Martijn Hans Van Gelderen**, Steinhausen (CH)

(73) Assignee: **Wonderland Switzerland AG**, Steinhausen (CH)

(**) Term: **15 Years**

(21) Appl. No.: **35/518,399**

(22) Filed: **Sep. 16, 2022**

(80) **Hague Agreement Data**

Int. Filing Date: **Sep. 16, 2022**

Int. Reg. No.: **DM/226116**

Int. Reg. Date: **Sep. 16, 2022**

Int. Reg. Pub. Date: **Sep. 22, 2023**

(30) **Foreign Application Priority Data**

Mar. 18, 2022 (CN) 202230142309.X

(57) **CLAIM**

The ornamental design for a lock for safety belts as shown and described.

DESCRIPTION

1. Lock for safety belts

1.1 : Perspective

1.2 : Front

1.3 : Back

1.4 : Left

1.5 : Right

1.6 : Top

1.7 : Bottom

(Continued)

The broken lines are shown for the purpose of illustrating parts of the article that form no part of the claimed design.

1 Claim, 7 Drawing Sheets
